UNITED STATES PATENT OFFICE.

MARION F. BENCH, OF CHILlicothe, MISSOURI, AND OTTO F. ROHWEDDER, OF DAVENPORT, IOWA.

DESIGN FOR A BREAD-DISPLAY RACK.

Application filed July 1, 1926. Serial No. 18,223. Term of patent 3½ years.

To all whom it may concern:

Be it known that we, MARION F. BENCH, a citizen of the United States, residing at Chillicothe, in the county of Livingston and State of Missouri, and OTTO F. ROHWEDDER, a citizen of the United States, residing at Davenport, in the county of Scott and State of Iowa, have invented a new, original, and ornamental Design for Bread-Display Racks, of which the following is a specification, reference being had to the accompanying drawing, forming part thereof.

The figure is a perspective view of a bread display rack of our design.

We claim:

The ornamental design for a bread display rack as shown.

MARION F. BENCH.
OTTO F. ROHWEDDER.
